UNITED STATES PATENT OFFICE.

CHARLES D. P. GIBSON, OF JERSEY CITY, NEW JERSEY, ASSIGNOR TO A. & W. S. CARR COMPANY, OF NEW YORK, N. Y.

PORTABLE HEATING APPARATUS.

SPECIFICATION forming part of Letters Patent No. 320,648, dated June 23, 1885.

Application filed May 27, 1884. (No model.)

To all whom it may concern:

Be it known that I, CHARLES D. P. GIBSON, of Jersey City, in the county of Hudson and State of New Jersey, have invented an

5 Improvement in Portable Heating Apparatus, of which the following is a specification.

This invention relates to a portable steam-heating apparatus that may be placed in a room or compartment and actuated by a gas-flame or a flame from kerosene or other hydro-carbon, the object being to obtain a large area of radiating-surface, so as to impart to the atmosphere the warmth and healthful condition resulting from the use of steam, and to apply 10 the apparatus under circumstances where an ordinary steam-generator is not available.

In the drawings, Figure 1 is an elevation of the apparatus, partially in section, and Fig. 2 is a plan view of the same below the line *xx*.

20 The vertical tubes *a* are of the usual character employed in steam-radiators. They are closed at the upper ends, and may receive an ornamental cap, *b*, and at the lower ends they open into the hollow base *D*. At one end of this base *D* is the circulating-pipe *e*, with an *X* branch that connects with the bends or *T* of the leg-tubes *f*, and at the other end of the base *D* is the elbow and vertical pipe *g*, with *X*-connections to the *T*-pieces of the vertical 25 leg-tubes *h*. The leg-tubes *f* and *h* are connected by the pipes *k*. These leg-tubes are preferably filled with water, as well as the other portions of the apparatus below the base *D*, which portions consist of the enlarged tube 30 or cylinder *l*, connected at its upper end with the lower end of the pipe *g*, and at its lower end with a branch pipe, *m*, that extends to a coil, *n*, and there is a branch pipe at the upper end of the coil leading to the circulating-pipe *e*.

40 There should be an air-cock at *i*, and a filling-plug at *p*, and a try-cock at *o*.

It will now be understood that when the apparatus is filled with water so that it rises in the base *D* above the pipes *e* *g*, as indicated 45 in the drawings, said water will be made to circulate through the apparatus by the action of heat applied to the coil *n*, and that as said water circulates and becomes heated the steam will be generated and pass up into the 50 radiating-tubes and expel the air by the cocks *i* or *o*, after which such cocks are to be closed,

and the apparatus will warm the room or compartment by the radiation from its surface and by the warming of the atmosphere that circulates around it.

55

It is preferable to apply a water-pipe, *q*, with a descending trap, and a gage at *r*, to indicate the pressure that may be generated in the apparatus.

Around the coil *n* a case, *s*, is placed. The same is open at the bottom, and there is a small hole at the top, so that the gases and products of combustion can pass away, and a pipe may be connected at this hole for conveying away such products of combustion to a 60 chimney or other escape flue or opening.

The coil may be heated by a flame from any ordinary or desired source, and I make use of a diaphragm within the case *t* to regulate the volume of the flame, and also the proximity 70 of such flame to the coil.

The burner *n* is of any suitable character. I have shown branch pipes that are perforated for the gas-flame jets, and the lower end of the burner-tube *n* is connected by a flexible or 75 jointed tube with the gas-supply pipe *v*. This pipe is supported by the coupling and stand *v* upon the pipe *k*, and upon a portion of the gas-pipe there is a fulcrum, *3*, for the forked lever *w*, the fork of which is pivoted to a ring 80 or cup around the burner-tube, and the other end of said lever *w* is connected to the diaphragm in the case *t*, so that when the pressure of steam increases and the diaphragm is forced down the burner is raised so as to come 85 closer up to the coil. I make use of the increased pressure to partially shut off the supply of gas or burning-fluid, and in so doing the height of the flame is lessened; hence the object of lifting the burner is to bring the flames 90 which are smaller up into proper proximity to the heating-coil.

The cock *y* is for regulating the supply of gas, and I make use of a lever-arm, *4*, to such cock, and place the same in a position for the 95 diaphragm to act upon it, and thereby lessen the flow of gas or burning-fluid as the pressure increases or the reverse.

There are burners in the market that are supplied by a pipe with liquid hydrocarbon, 100 and in which the supply is regulated by a cock; hence it is to be understood that the

burner, the pipe, and the cock represented are to be of any known or desired character for burning ordinary illuminating-gas or non-luminous heating-gas or liquid hydrocarbon.

I claim as my invention—

1. The combination, with the radiator-pipes and base and the pipes *e g.*, of the circulating-cylinder *l* and pipe *m*, and the coil *n*, connecting the pipes *e g.*, and a burner for heating the coil, a case and diaphragm acted upon by the pressure in the apparatus, a cock for regulating the supply of combustible material, and connections from said diaphragm to said cock and to the burner, whereby the supply of gas or fluid is regulated and the burner raised or lowered by the pressure upon said diaphragm, substantially as specified.

2. The combination, with the radiator-pipes and base and the pipes *e g.*, of a heating-coil, a case for the same, and pipes connecting said coil to the radiating-pipes and base, a burner, and a lever and diaphragm for raising and lowering said burner, and a cock and connection to the diaphragm to admit the burning gas or fluid, substantially as set forth.

Signed by me this 13th day of May, A. D. 1884.

CHAS. D. P. GIBSON.
